(57) **CLAIM**

The ornamental design for a control box, as shown and described.

DESCRIPTION

FIG. 1 is a perspective front side view of a first embodiment of a control box seen from the top;

FIG. 2 is a perspective rear side view seen from the bottom thereof;

FIG. 3 is an elevational front side view thereof;

FIG. 4 is an elevational rear side view thereof;

FIG. 5 is an elevational left side view thereof;

FIG. 6 is an elevational right side view thereof;

FIG. 7 is a top plan view thereof;

FIG. 8 is a bottom plan view thereof;

FIG. 9 is a perspective front side view of a second embodiment of a control box seen from the top;

FIG. 10 is a perspective rear side view seen from the bottom thereof;

FIG. 11 is an elevational front side view thereof;

FIG. 12 is an elevational rear side view thereof;

FIG. 13 is an elevational left side view thereof;

FIG. 14 is an elevational right side view thereof;

FIG. 15 is a top plan view thereof; and,

FIG. 16 is a bottom plan view thereof.

FIGS. 1-8 for the first embodiment are black and white drawings. In the second embodiment, the stippled areas in FIGS. 9-11 and FIGS. 13-15 are shown to represent contrasting surfaces to adjacent non-stippled areas.

1 Claim, 16 Drawing Sheets
